COMBINED WASHER AND WIPER UNIT

Francis E. Lorenz, Jr., 383 S. Brimhall,
St. Paul, Minn. 55105

Filed Aug. 26, 1968, Ser. No. 13,264

Term of patent 14 years

Int. Cl. D7—06

U.S. Cl. D49—21

FIG 1

FIG 2

FIG 3

FIG 4

FIG 5

FIG 6

FIG 7

FIGURE 1 is a front perspective view of a combined washer and wiper unit showing my new design;

FIGURE 2 is a back elevational view of FIGURE 1;

FIGURE 3 is a bottom view of FIGURE 1;

FIGURE 4 is an end elevational view of FIGURE 1;

FIGURE 5 is a front perspective view of a modified embodiment of the combined washer and wiper unit shown in FIGURE 1;

FIGURE 6 is a back elevational view of FIGURE 5; and

FIGURE 7 is a bottom view of FIGURE 5.

The opposite ends of the washer and wiper units shown in FIGURES 1 and 5 are identical as shown in FIGURE 4.

I claim:

The ornamental design for a combined washer and wiper unit, substantially as shown and described.
